UNITED STATES PATENT OFFICE.

CHARLES BUTCHER, OF CAMBRIDGE, MASSACHUSETTS.

INLAID FLOOR OR WOOD COVERING.

SPECIFICATION forming part of Letters Patent No. 396,917, dated January 29, 1889.

Application filed August 10, 1888. Serial No. 282,437. (No model.)

To all whom it may concern:

- Be it known that I, CHARLES BUTCHER, a citizen of the United States, and a resident of Cambridge, in the county of Middlesex and State of Massachusetts, have invented new and useful Improvements in Inlaid Floors or Wood Coverings, of which the following, taken in connection with the accompanying drawings, is a specification.
- This invention relates to improvements in floors and ceilings, as well as wainscoting or panelings; and it has for its object the production of an inlaid floor or surface at a very reduced cost and simplicity of manufacture, as will hereinafter be more fully shown and described, reference being had to the accompanying drawings, wherein—
- Figure 1 represents a plan view of the invention. Fig. 2 represents a cross-section on the line A B, shown in Fig. 1; and Fig. 3 represents a side elevation of one of the inlaid boards.
- Similar letters refer to similar parts wherever they occur on the different parts of the drawings.
- In making my improved floor, ceiling, &c., I take boards *a a* of suitable length and width, in the top of which I make lateral recesses *a' a'*, right-angled, curved, or diagonal, according to the pattern to be produced, and in said recesses are inserted and glued the blocks *b b b*, having the grain preferably crossing that of the grain of the boards *a a*, as shown. In the sides of the boards *a a*, I make longitudinal grooves *a'' a''*, one in each side of said boards, which grooves pass alternately through the board *a* and its inserted blocks *b b*, as shown in the drawings. In said grooves are inserted the thin metal tongues *c c*, which serve not only to hold the sides of the boards *a a* together, so as to prevent one from rising or falling below the other in the series, but said metal tongues also serve for the purpose of holding permanently the blocks *b b* in position relative to the boards *a a*, as shown. The metal tongues *c c* are provided with elongated slots or perforations *c' c'*, through which are driven in a slanting direction the fastening-nails *d d*, said nails passing through the lower portion of the boards *a a* and the lateral inlaid blocks *b b*, as shown, their points being driven into the lower floor or joist *e* below, as shown in Fig. 2.
- It is essential that the side grooves, *a'' a''*, should pass alternately through the edges of the main boards *a a* and the lateral inlaid blocks *b b*, so as to cause the metal tongues *c c* to rest alternately in grooves in such boards and its lateral blocks or inlaid pieces *b b*, for the purpose of holding such respective parts together, and thus preventing the upper surfaces of said blocks from warping or rising above or below the upper surfaces of the boards *a a*, and thus preserving and maintaining a uniform and even upper surface of the floor or wood covering.
- In Fig. 1 of the drawings I have shown a checker-board pattern produced by my improved floor or wood covering; but this is not essential, as any other desirable pattern may be produced, according to the shapes or sizes of the blocks *b b* relative to the boards *a a*, without departing from the essence of my invention. The floor or wood covering thus produced has every appearance of a costly inlaid floor, in which the component parts are firmly united and held together so as to prevent any warping or irregularity of surface whatsoever.
- What I wish to secure by Letters Patent and claim is—
- The improved floor or wood covering, as described, consisting of the boards *a a*, having lateral or equivalent recesses *a' a'*, and the blocks *b b*, inserted in said recesses, in combination with the metal tongues *c c* and grooves *a'' a''* in the sides of said boards, said grooves passing alternately through the edges of the boards and the blocks *b b*, substantially as and for the purpose set forth.
- In testimony whereof I have signed my name to this specification, in the presence of two subscribing witnesses, on this 13th day of April, A. D. 1888.

CHARLES BUTCHER.
